CARPENTER'S DIVIDER

William J. Des Roberts, Biddeford, Maine

Application October 13, 1932, Serial No. 637,665

3 Claims. (Cl. 33—149)

My invention relates generally to dividers and particularly to carpenters' dividers, and an important object of my invention is to provide a device of this character which may be used with convenience and accuracy in confined spaces such as are encountered in carpentry and the like work when fitting beams and the like in corners and small spaces.

It is also an important object of my invention to provide dividers of this character which are extremely rugged in construction without being expensive to manufacture, and which are economical also in the respect of affording means for using a pencil to a very short length without requiring replacement thereof.

It is also an important object of my invention to provide means for holding the pencil in adjusted positions, which means permit quick, accurate and easy adjustment of the projection of the pencil and an accurate relation of the pencil to the remainder of the dividers.

Other objects and advantages of my invention will be apparent from a reading of the following description in connection with the drawing, wherein for purposes of illustration I have shown a preferred embodiment of the invention.

In the drawing:

Figure 1 is a general side elevational view of the embodiment.

Figure 2 is a side elevational view of one leg of the embodiment.

Figure 3 is an edge view of Figure 2.

Figure 4 is a sectional view through the other leg.

Figure 5 is an edge view of Figure 4 and

Figure 6 is a transverse sectional view taken approximately on the line 6—6 of Figure 1.

Referring in detail to the drawing, wherein like numerals refer to like parts throughout the same, the numeral 5 generally designates the embodiment which comprises the complete leg 6 and the pencil carrying leg 7.

The complete leg 6 comprises a short rectangular straight portion 8 whose lower end merges into a downwardly tapered portion 9 which terminates in a sharp point 10.

It will be observed that the tapered portion 9 is not arranged in axial extension of the rectangular or squared portion 8, but is arranged at an angle to the longitudinal axis of the portion 8 so as to be directed slightly toward the pencil carrying leg 7.

The upper end of the squared portion 8 is curvilinearly reduced so as to produce the shoulders 11 and 12 defined by a circular plate 13 which is ar-

ranged concentrically of the curvatures of the shoulders 11 and 12 and thereby assumes a position offset from the longitudinal axis of the squared portion 8 as seen in Figure 2. This plate 13 is provided with a central opening 14.

The pencil carrying leg 7 has an upper portion 15 similar to the upper portion 8 of the complete leg. As at the portion 16 at the lower end of the portion 8 of the leg 6, the pencil carrying leg 7 has at the lower end of the squared portion 15 a merger 17 into downwardly tapered portion 18 which is at an angle to the portion 15 similar to the angle which the portion 9 has to the portion 8 of the companion leg. However, instead of being tapered to a sharp point like the companion leg 6, the portion 18 of the pencil carrying leg 7 is laterally enlarged as indicated at 19 to provide a semi-circular channel for receiving the side of the pencil 20. The lower end of the portion 18 of the pencil carrying leg 7 is cut off flatly at 21 much above the point 10 of the companion leg. At the upper part of the enlargement 19 of the portion 18 of the pencil carrying leg there is provided a laterally extending block 22 which is arranged at an angle to both the portion 15 and the portion 18 of the pencil carrying leg. This block 22 is provided with a bore 23 vertically formed therein to slidably receive the pencil 20 through the block. The bore 23 is of a size to fairly snugly receive a standard size pencil 20 and hold the same in slidable engagement with the channel in the lower part of the leg, so that engagement of the parts is preserved without binding. For holding the pencil against upward movement and for giving it the proper frictional engagement in the channel and in the bore 23, I provide a spring member 24 which is inserted and held in a suitable opening 25 outward of the opening 23 in the block 22. This spring member 24 has a portion 26 which is sharpened at its lower end. This portion 26 is angularly directed toward the pencil 20 and is adapted to engage the sharpened end against the side of the pencil so that the pencil may be readily moved downwardly but will not slip upwardly from an adjusted position. It will be observed that the effective end of the spring member 24 engages a lower part of the pencil so that this part of the pencil is forcibly urged into proper relation with the channel in the lower part of the leg and preserved in the proper alignment with the leg and the upper part of the switch is held by the edges of the bore 23 for promoting accurate work when the divider is used.

The upper end of the portion 15 of the pencil carrying leg 7 has, instead of the single circular 55

plate 13 a pair of circular plates 27, 28 between which is received the single plate 13 of the complete leg of the divider. The plates 27, 28 are provided with central openings 29. The openings 14 in the plate 13 and the openings 29 in the plates 27, 28 are to be registered and have passed therethrough a bolt 30 which has on one end thereof a thumb nut 31 which may be tightened thereon for securing the legs in adjusted relation to each other in an obvious manner.

The comparatively great size and bulk of the plates 13 and 27, 28 provide an unusual bearing surface of great strength and ruggedness, while the heavy construction of the leg and their formation also contribute to the ruggedness and mechanical efficiency of the device of my invention. The shortness of the leg comparatively speaking, also helps the maneuverability of the device in small places and in corners. However, the comparatively great length of the tapered portions of the legs compared to the straight portions thereof enables marking arcs and circles of relatively great diameter, which condition is aided by the slight inward direction of the lower tapered parts of the legs.

It is to be observed that the point of the pencil 20 is enabled to have a true relation to the leg 6, thereby promoting accuracy and balance in the device therein.

Though I have shown and described herein a preferred embodiment of my invention, it is to be definitely understood that I do not desire to limit the application of my invention thereto, and any change or changes may be made in material and structure and arrangement of parts, within the spirit of the invention and the scope of the subjoined claims.

It will be observed that the means provided for mounting a pencil on the leg 7 permits the use of either a full length or of shorter pencils without any interference with the operation of the dividers and that the pencil-gripping action, while effective, is such as to permit the use of chalk pencils as well as of wooden pencils. The arrangement of the pencil receiving channel at the precise angle necessary to bring the point of the pencil into opposed angular relation to the point of the leg 6 makes accurate drawing with either chalk or lead pencil feasible. In the closed position of the legs, the pencil being properly ad-

justed, the point of the pencil will be at the point of the leg 6 and the straight parts 8 and 15 of the legs will be parallel. However, if the pencil be adjusted too short this parallel relation will not be present and the pencil point will not meet the point of the leg 6 and inaccurate work will result.

Having thus described my invention, what I claim as new is:

1. In carpenters' dividers including a pair of legs, pencil carrying means on the outer side of one of said legs, said means comprising a block having a pencil receiving bore, a portion of said means being provided with a channel with which said bore communicates, said channel being angulated with respect to said one leg to permit a pencil located in said bore and channel to extend a relatively great distance above said block, and spring means extending downwardly from said block and having a sharpened portion engaging the side of the pencil below said block to clamp the pencil in said bore and channel.

2. In carpenters' dividers including a pair of legs having lower portions angulated toward each other, one of said portions having a divider point, pencil holding means on the outward side of one of said legs including a block provided with a pencil receiving bore, a portion on said leg's lower portion provided with a channel communicating with said bore, a pencil in said bore and channel, a spring extending from said block and having a sharpened portion yieldably engaging the pencil below said block, the upper portions of the legs being substantially parallel when said pencil is correctly adjusted with its point in companion relation to the divider point.

3. In a carpenter's divider including a pair of legs, pencil holding means on one of said legs, said means including a block having a pencil receiving bore angulated with respect to said one leg, a member on said one leg provided with a channel communicating with said bore and substantially aligned therewith, a spring projecting from said block and having an angulated sharp end portion, a pencil in said bore and channel, said sharp end portion engaging the pencil below said block to force the pencil against sides of said channel and said bore to clamp the same therein and against longitudinal movement in one direction.
